UNITED STATES PATENT OFFICE.

WILLIAM H. RICE, OF TIGER, GEORGIA.

COFFERDAM CONSTRUCTION.

1,418,879.

Specification of Letters Patent. Patented June 6, 1922.

Application filed October 3, 1921. Serial No. 505,001.

To all whom it may concern:

Be it known that I, WILLIAM H. RICE, a citizen of the United States of America, residing at Tiger, in the county of Rabun and 5 State of Georgia, have invented new and useful Improvements in Cofferdam Constructions, of which the following is a specification.

The object of the invention is to provide a 10 cofferdam for use in the building of piers and like structures under water and under conditions necessitating the restraining or shifting of mobile soils or substances during the erection of a foundation supported upon 15 bed rock and designed to facilitate the formation of the foundation and the location of the caisson and retaining it in proper position for the protection of the masons and other workmen during the erection of the 20 pier or like structure; and with this object in view the invention consists in a construction and combination of parts of which a preferred embodiment is shown in the accompanying drawings, wherein:—

25 Figure 1 is a plan view, and

Figure 2 is a vertical sectional view of a cofferdam construction embodying the invention.

The device consists essentially of a base 30 member 10 and what may be termed a super-structure 10^a, the former being provided with a shell 11 constituting a form or mold reduced at its lower edge as shown at 12 to facilitate the penetration of the mud, sand 35 and like substances found at the bottom of bodies of water covering the bed rock indicated at 13, said shell consisting of uprights held in place and reinforced by braces 14 or the equivalents thereof.

40 Rising from the base and suitably secured at their lower ends thereto are uprights or posts 15 consisting of relatively heavy timbers disposed for example in the angles of the form or mold represented by the base 45 and extended to and above the normal surface or level of the water in the watercourse or body in which the pier is to be located, the space marked out by the positions of said posts or uprights representing the precise 50 position of the pier to be built and which

when constructed, after the removal of the sand and mud from the interior of the caisson, by dredging or by the use of a sand pump or equivalent means, will consist of concrete or cement introduced to fill the form 55 or mold and produce a foundation as indicated at 16.

Surmounting the base member and guided by the post or uprights 15, which as above noted extend above the plane of the surface 60 of the water, is the upper member or caisson which may be reinforced by upright braces 17 and horizontal braces 18 supplemented if desired by the diagonal braces 18^a to afford sufficient strength to restrain or resist 65 the inward pressure of the water surrounding the caisson after the contents thereof have been removed as above indicated by pumping or dredging or both. Said upper member or caisson preferably embodies the 70 timber fillers 19 constituting the walls which are preferably provided exteriorly with a sheet metal sheathing or jacket 20 which extends from the upper edges of the walls to a plane below the lower edge of the 75 walls, and the surplus material below the lower edges of the walls is inturned or flanged as shown at 21 to lie between the lower edges of the walls of the upper member 80 or caisson and the upper edges of the walls of the lower or base member and to project into the space enclosed by the base member so that when the concrete or cement to constitute the foundation is introduced into the structure reaches the proper level, 85 these flanges will be embedded therein and will constitute a watertight seal to prevent the water from leaking through the walls of the composite structure between the lower edges of the walls of the superstructure and 90 the upper edges of the walls of the base, and thereby detracting from or threatening the stability of the completed structure. The cofferdam is designed to be built above the surface of the water on any suitable support such as barges or false work and then submerged and sunk until the lower edges 95 of the walls of the base come in contact with the bed rock after penetrating the relatively soft mud or sand bottom, and this sinking 100

operation may be accomplished by the use of any convenient weighting means such as rocks 22 arranged for example on platforms 23 supported by longitudinal beams 24 which in turn rest upon transverse beams 25 spanning the upper end of the caisson. Or the base member of the structure may be sunk and the superstructure or caisson applied thereto after the base has reached 10 its seat on the bed rock.

Having positioned the parts with the base properly seated on the bed rock, however, the next operation is to remove the mud and sand from the interior of the base by the use of 15 dredges, sand pumps or the equivalent thereof, and this having been accomplished permanent anchoring means may be introduced such as the I-beams 26 suspended in the structure by means of cables 27 depending 20 from the cross beams 25 or any equivalents thereof so that the weight of the I-beams or like structural iron elements is imposed upon the upper edge of the superstructure or caisson while the beams are located near the 25 bottom of the base enclosure and close to the bed rock. These structural iron beams are lowered as will be observed after the mud and sand have been cleaned out of the interior of the cofferdam and may rest if desired 30 on the rock footing so that when the concrete or cement is introduced they will become embedded therein and the entire weight of the concrete foundation will be utilized in holding the caisson in place.

35 The concrete or cement may be introduced into the mold formed by the structure by means of a tremie tube or its equivalent to build up a foundation of dimensions designed by the walls of the base member of 40 the structure to the prescribed or predetermined depth to embed the break joint flanges 21 of the superstructure or caisson, and thereafter, when the concrete or cement has become sufficiently set the water contained in 45 the watertight caisson from which moisture is excluded by the joint formed by said flanges 21, may be removed by pumps or the like to permit of the operations of the masons and other workmen on the building or 50 construction to be erected upon the foundation formed by the concrete or cement base previously laid.

Having described the invention, what is claimed as new and useful is:—

55 1. A cofferdam construction having a base member constituting a mold or form for a concrete or cement foundation, an upper member or caisson supported by the base member and having an enclosing wall, and 60 anchoring means for the upper member having an element disposed within the base member and adapted to be embedded in the concrete or cement molded or formed therein.

65 2. A cofferdam construction having a base member constituting a mold or form for a

concrete or cement foundation, an upper member or caisson supported by the base member and having an enclosing wall, and anchoring means for the upper member having an element disposed within the base member and adapted to be embedded in the concrete or cement molded or formed therein, the base having a wall provided with reduced lower edges for facilitating the sinking thereof in the mud and sand at the bottom of a body of water. 75

3. A cofferdam construction having a base member constituting a mold or form for a concrete or cement foundation, an upper member or caisson supported by the base member and having an enclosing wall, and anchoring means for the upper member having an element disposed within the base member and adapted to be embedded in the concrete or cement molded or formed therein, the base member carrying uprights or posts extending to and above the upper surface of the water for holding and guiding the upper member or caisson. 80 85

4. A cofferdam construction having a base member constituting a mold or form for a concrete or cement foundation, an upper member or caisson supported by the base member and having an enclosing wall, and anchoring means for the upper member having an element disposed within the base member and adapted to be embedded in the concrete or cement molded or formed therein, the base member carrying uprights or posts extending to and above the upper surface of the water for holding and guiding the upper member or caisson, which is arranged to enclose the same. 90 95 100

5. A cofferdam construction having a base member constituting a mold or form for a concrete or cement foundation, an upper member or caisson supported by the base member and having an enclosing wall, and anchoring means for the upper member having an element disposed within the base member and adapted to be embedded in the concrete or cement molded or formed therein consisting of pendent structural beams located within the space bounded by the base and caisson. 105 110 115

6. A cofferdam construction having a base member constituting a mold or form for a concrete or cement foundation, an upper member or caisson supported by the base member and having an enclosing wall, and anchoring means for the upper member having an element disposed within the base member and adapted to be embedded in the concrete or cement molded or formed therein, and consisting of structural iron beams 120 located within the base member and suspended by cables from the upper portion of the caisson. 125

7. A cofferdam construction having a base member constituting a mold or form for a 130

concrete or cement foundation, an upper member or caisson supported by the base member and having an enclosing wall, and anchoring means for the upper member having an element disposed within the base member and adapted to be embedded in the concrete or cement molded or formed there-

in, the caisson having an exterior sheathing or jacket inturned at the lower edges of the walls thereof for embedding in the cement or concrete contents of the base member.

In testimony whereof I affix my signature.

WILLIAM H. RICE.
